UNITED STATES PATENT OFFICE.

FREDERICK J. BOWMAN, OF CLEVELAND, OHIO, ASSIGNOR TO THE GRASSELLI CHEMICAL COMPANY, OF CLEVELAND, OHIO, A CORPORATION OF OHIO.

ORE-TREATING FURNACE.

1,399,046.

Specification of Letters Patent.

Patented Dec. 6, 1921.

Application filed December 29, 1917. Serial No. 209,410.

To all whom it may concern:

Be it known that I, FREDERICK J. BOWMAN, a citizen of the United States, and a resident of Cleveland, county of Cuyahoga, 5 and State of Ohio, have invented a new and useful Improvement in Ore-Treating Furnaces, of which the following is a specification, the principle of the invention being herein explained, and the best mode in 10 which I have contemplated applying that principle so as to distinguish it from other inventions.

The present invention, relating as indicated to an ore roasting furnace, has more 15 particular regard to a roasting furnace adapted to remove the sulfur from various kinds of ore in the form of sulfur dioxide gas. One of the primary objects of the present invention is the provision of a means 20 for accomplishing this purpose, which shall make it possible to recover a greater percentage of the sulfur in the ore than is possible in the various types of apparatus now in general use, in all of which there is 25 a certain amount of waste. Another object of the invention is to secure this desired result without undue complication of the furnace and its parts and without the use of an unusual amount of heat. To the accomplishment of the foregoing and related ends, 30 said invention, then, consists of the means hereinafter fully described and particularly pointed out in the claims.

The annexed drawing and the following 35 description set forth in detail certain mechanism embodying the invention, such disclosed means constituting, however, but one of various mechanical forms in which the principle of the invention may be used.

40 In said annexed drawings:—

Figure 1 is a vertical section of a roasting furnace broken in the center constructed and designed to carry out the present invention; Fig. 2 is a second vertical section thereof taken upon a plane at right angles to the plane of the section of Fig. 1; Fig. 3 is a vertical section of a portion of the air heating passage and showing baffles therein; and Fig. 4 is a horizontal section of the base of 50 furnace showing the disposition of the several flues and passages in the walls thereof.

The general construction and arrangement of passages and chambers in my improved type of furnace is best shown in 55 Figs. 1 and 2, the furnace consisting of a

substantially rectangular vertically arranged chamber 1 into which finely divided ore is admitted through openings 2 in the top connected with a hopper 3. The ore which is admitted through the openings 2 from the 60 hopper is permitted to fall substantially vertically through the chamber 1 into a tapered passage 4 formed in the bottom of the furnace and connecting by means of a passage 5 with any suitable source of deposit 65 for the treated ore, this passage being controlled by means of a hinged valve or gate 6.

The furnace chamber 1 is conveniently heated by means of encircling passages 7 which are formed in the walls of the chamber 70 1 and which are connected to a fire chamber 8, located at any suitable point adjacent to the bottom of the furnace. These heating passages or flues 7 are connected together and are adapted to discharge at a suitable 75 point, as through passage 7'. The inner walls of the chamber 1 are provided with a series of inwardly extending heating units 9 connecting to the passages 7 by means of openings 10 in the walls and constructed to 80 present an inclined surface 11 to the descending material. The preferred construction of these heating units or chambers is also of interest as the main heated surface 11 is formed on a single readily removable refractory member, which may be replaced within a minimum of time when necessary 85 by entrance into the furnace through a suitable manhole in the walls thereof.

Outside of heating passages or flues 7 90 there are formed air (or oxygen) heating passages 12 through which air is drawn slowly through openings 12' over baffle plates 13, shown in Fig. 3, in order to increase the distance traveled as much as possible and secure as high a temperature as can be maintained with a given temperature in the heating flues 7. These air heating passages 12 are connected at their upper ends by means of ducts 14 extending to and 100 communicating with the top of the chamber 1 directly below the end of the passages 2, and through which ducts the air is introduced into this chamber. The conduits 14 may be connected to the furnace 105 chamber at a number of spaced points, 26 27, throughout this chamber in order that air may be furnished through the chamber at different elevations to insure a sufficient supply at all points in the chamber to secure a 110

burning of all of the material falling therethrough. In this way the finely divided ore which falls into the chamber from the hopper is immediately and thoroughly mixed 5 with the heated air or oxygen coming from the ducts 12. The draft through the chamber 1 is of course in a downward direction and this draft may be produced in various ways, an exhauster being used for the purpose if desired and located in connection 10 with a lateral discharge opening 15 at the bottom of the furnace, through which the gases produced during the roasting of the ore are removed.

15 Disposed in the chamber 1 are a large number of relatively small triangular heating elements 16, these elements 16 being constructed of some suitable refractory material and being heated by the heating flues 7 20 and by the burning sulfur passed thereover to a high temperature, which in most cases will maintain these at incandescence. It will be noticed that the heating elements 16 are disposed in horizontal rows with their 25 apices uppermost and are alternated so that between and beneath every two elements there is another element positioned with one edge uppermost and approximately directly between the center of the space between the 30 two members 14 above it. In this way the ore dropping into the chamber is spread over the entire area and every time a quantity of this ore strikes against one of the heating elements 16 it is divided into two parts which 35 slide along opposite sides of the element 16 and are heated in this process. The chamber 1 is of any suitable height and the elements 16 are relatively small and very numerous so that in the course of its passage 40 from the top to the bottom in this chamber the ore is maintained at a substantially even and high temperature by reason of contacting the elements 16 throughout its passage through this chamber. The effect of the 45 present construction and arrangement of the heating elements is such as to produce a large number of thin sheets or columns of fine ore falling through the chamber at an angle to the central plane of this chamber 50 and at an angle to the path of movement of the air or oxygen passing therethrough. Thus at all times the ore is in contact with air or oxygen, and as the sulfur in the ore is heated to the required temperature it is 55 entirely burned into sulfur dioxid gas, the sulfur combining with the oxygen present or with the oxygen in the air.

Formed in the walls of the chamber 1 are a large number of regularly spaced recesses 60 or collecting pockets 30 which serve to collect some of the finely divided material descending through the furnace, and which permit convenient access to the chamber of a scraper or other tool for purposes of cleaning the baffles 16 when desired, since the

pockets are closed by removable members or plugs 17 of refractory material.

It has been found possible with the present type of furnace to secure practically a complete removal of the sulfur present in 70 the ore, this sulfur dioxid being removed from the chamber through the discharge opening 15.

The members 16 are supported at either end in pockets or seats 40 and extend across 75 the furnace chamber, these pockets or seats 40 being suitably formed in the walls of said chamber.

Other modes of applying the principle of my invention may be employed instead of 80 the one explained, change being made as regards the mechanism herein disclosed, provided the means stated by any of the following claims or the equivalent of such stated means be employed.

I therefore particularly point out and distinctly claim as my invention:—

1. In an ore roasting furnace, the combination of a roasting chamber, a plurality of triangular heated elements disposed in 90 transverse rows with their apices uppermost, the elements in each row being arranged to lie between the elements of the next adjacent rows, means for introducing finely divided ore at one end of said chamber, and other means adapted to supply heated oxygen at the same end.

2. In an ore roasting furnace, the combination of a roasting chamber, a plurality of triangular heated elements disposed in 100 transverse rows with their apices uppermost, the elements in each row being arranged to lie between the elements of the next adjacent rows, means for introducing finely divided ore at one end of said chamber, other means 105 adapted to supply heated oxygen at the same end, a reservoir at the opposite end of said chamber adapted to collect the treated ore, and exhaust means disposed adjacent said reservoir and adapted to discharge the gases 110 produced during the treatment of such ore.

3. In an ore roasting furnace, the combination of a roasting chamber, a plurality of heated elements disposed in such chamber, said chamber being formed with a plurality of collecting recesses in the walls thereof, means for introducing finely divided ore at one end of such chamber, and other means adapted to supply heated oxygen at the same end.

4. In an ore roasting furnace, the combination of a roasting chamber, a plurality of heated elements disposed in transverse rows, said chamber being provided with a plurality of collecting recesses disposed beneath the ends of said heated elements, means for introducing finely divided ore at one end of said chamber, and other means adapted to supply heated oxygen at the same end.

5. In an ore roasting furnace, the combination of a roasting chamber, a plurality of triangular heated elements disposed in transverse rows with their apices uppermost, the elements in each row being arranged to lie beneath the elements of the next adjacent row, said chamber being formed with a plurality of collecting pockets disposed beneath the ends of each of said 10 heated elements, said pockets being adapted to collect a portion of the material treated in said furnace, means for introducing finely divided ore at one end of said chamber, and other means adapted to supply heated oxygen at the same end.

transverse rows with their apices uppermost, the elements in each row being arranged to lie beneath the elements of the next adjacent row, said chamber being formed with a plurality of collecting pockets disposed beneath the ends of each of said 20 heated elements, said pockets being adapted to collect a portion of the material treated in said furnace, removable plugs mounted in the walls of said chamber and adapted when removed to permit access to such pockets, means for introducing finely divided ore at 25 one end of said chamber, and other means adapted to supply heated oxygen at the same end.

Signed by me, this 24th day of December, 1917.

FREDERICK J. BOWMAN.

6. In an ore roasting furnace, the combination of a roasting chamber, a plurality of triangular heated elements disposed in
